(57) **CLAIM**

The ornamental design for an cup insert for wireless brassiere, as shown and described.

DESCRIPTION

FIG. 1 is a front elevation view of a cup insert for wireless brassiere showing our design;

FIG. 2 is a detail view of a portion of FIG. 1; and,

FIG. 3 is a side view of FIG. 1.

The broken lines shown in FIG. 1 are for the purpose of illustrating the detailed portion of FIG. 1 shown in FIG. 2, and forms no part of the claim. The dot dash broken line in FIGS. 1 and 2 indicate cutoff boundaries for enlarged detailed portion view and form no part of the claim.

1 Claim, 2 Drawing SheetsFIG. 1

FIG. 2

FIG. 3
